UNITED STATES PATENT OFFICE.

JESSE F. COMSTOCK, OF WILKES-BARRE, PENNSYLVANIA.

MACHINE FOR FORMING ARMATURE COILS.

Application filed September 21, 1921. Serial No. 502,269.

To all whom it may concern:

Be it known that I, JESSE F. COMSTOCK, a citizen of the United States, residing at Wilkes-Barre, in the county of Luzerne 5 and State of Pennsylvania, have invented certain new and useful Improvements in Machines for Forming Armature Coils, of which the following is a specification.

This invention relates to machines for bending and twisting coils of wire into preferred forms for use in the armatures of electric machines; and it consists in the novel construction and combination of the parts hereinafter fully described and 15 claimed whereby the coil of wire previously wound into the form of an endless loop or link is bent and twisted to the required form.

In the drawings, Figure 1 is a front view 20 of a machine constructed according to this invention. Fig. 2 is a front view showing the outline of an armature coil after being bent and twisted, and not showing the separate wires. Fig. 3 is an end view of the 25 same. Fig. 4 is a cross-section through the machine, taken on the line 4—4 in Fig. 1, and drawn to a larger scale. Fig. 5 is a sectional plan view of one of the coil supports, taken on the line 5—5 in Fig. 4.

30 A supporting frame is provided, and is formed of two uprights 6 which are coupled together by a horizontal guide bar 7 at their upper parts, and two distance pieces 8 at their lower parts. The guide bar 7 is preferably cylindrical, and 10 are two carriages which are slidable longitudinally on it. These two carriages are splined to the guide bar, and have lugs 12 and adjusting screws 14 so that they can be adjusted to 35 slide freely on the guide bar without being extremely loose. The carriages are tightened on the guide bar by contracting them by means of the screws 14.

The carriages have flat supports 15 on 45 their upper sides, and 16 are supporting brackets which are secured to the supports 15 by screws 17.

The supports 15 have slots 18 for the screws 17. The supports 15 have also 50 grooves 19 and the brackets 16 have tongues 20 which are slidable in the grooves 19. The brackets are set at a suitable distance apart to suit the size of the coil, and are clamped to the supports by the screws. The brackets 55 have horizontal pins 21 for supporting the

ends of the coil of wire, and they have beveled portions 22 on their edges which are nearest to the center of the machine to permit the bending of the coil.

The wire of which the armature coil is 60 formed is wound into the form of a long link, and the end portions of this link are placed on the two pins 21 so that it is suspended between them.

A pair of arms, 24 and 25, is provided at 65 each end of the machine. The arms of each pair are formed right and left, and are pivoted on pins 26 which project from the uprights 6 under the guide bar 7. Each arm has a stop pin 27 which is adjustable 70 circumferentially in a curved slot 29 in the upright, and which operates to limit the movement of the arm. The curved slots are arranged concentric with the pivot pins 26. Each arm is provided with a sleeve 30 which 75 is adjustable longitudinally on it, and which is provided with a fastening screw 31, and each sleeve has an eye 32 on the side of it nearest to the guide bar 7.

The two arms 24 are arranged at the front 80 of the machine, and the two arms 25 are arranged at its rear part. A front bar 34 is arranged horizontally and is secured in the eyes 32 of the front arms 24, and a similar bar 35 is secured between the two rear arms 85 25, and is arranged parallel to the front bar 34.

Each horizontal bar 34 and 35 has two similar clamp blocks 36 secured on it by screws 37. The clamp blocks are adjustable 90 on the bars, and can be secured to them at any desired distance apart. The clamp blocks 36 of the front bar are arranged to project rearwardly, and the clamp blocks of the rear bar are arranged to project forwardly. Each clamp block 36 has a hook-shaped jaw 38 the stem of which is journaled in the free end portion of the block and provided with a locking screw 39. Each clamp block has also an adjustable jaw 40 100 100 which is provided with a slot 41, and a screw 42 for securing it in position.

The ends 45 of the wound coil are placed in engagement with the pins 21, and the clamping jaws are set at suitable distances 105 apart on the bars 34 and 35, and at suitable distances from the pivot pins 26 of the arms, so that they will engage with the longitudinal stretches 46 of the coil, which are then clamped in the clamping jaws, while 110

the stems of the hook-shaped jaws are substantially vertical. The arms 24 and 25 are then moved forcibly apart, by hand, to the positions shown in Fig. 4, and so that they engage with the stops. The stops ensure a number of coils being twisted and bent to the same extent. This movement of the arms bends and twists the armature coil to the form shown in Figs. 2 and 3, so that its longitudinal stretches are set at an angle to each other instead of being parallel, and so that the end portions 45 are set at an angle to the axis of the guide bar 7. The carriages 10 slide towards each other when the arms are moved apart. The carriages 10 slide freely, but their frictional resistance may be adjusted, if necessary, by means of the screws 14. Any suitable stops may be applied to limit the length of the sliding movements of the carriages 10, if desired, but they stop sliding automatically when the arms 24 and 25 strike the stops 27.

The various parts of this machine can be set and adjusted so that wire coils of different size and weight can be bent and twisted. The coils can also be bent and twisted to form differently proportioned coils to suit different armatures. The completed bent and twisted coil is removed from the machine by turning around the hook-shaped clamping jaws and permitting the arms to move towards each other a little, so as to permit the coil to be lifted out of the clamping jaws, the pins 21 being removed to free the ends of the coil.

What I claim is:

1. In an apparatus for operating on an armature coil with end portions and longitudinal stretches, a frame provided with slideable supports for engaging with the end portions of an armature coil, and front and rear arms pivoted to the said frame and provided with means for engaging with the longitudinal stretches of the coil, the said arms operating to bend and twist the coil when moved apart and crosswise of it.

2. In an apparatus for operating on an armature coil with end portions and longitudinal stretches, a frame provided with a longitudinal guide bar, carriages slideable on the guide bar and provided with means for engaging with the end portions of an armature coil, and front and rear arms pivoted to the frame and provided with means for engaging with the longitudinal stretches of the coil.

3. In an apparatus for operating on an armature coil with end portions and longitudinal stretches, a frame provided with a longitudinal guide bar, carriages slideable on the guide bar, laterally adjustable brackets secured on the said carriages, pins supported by the said brackets and adapted to engage with the end portions of an armature coil, and front and rear arms pivoted to the

frame and provided with means for engaging with the longitudinal stretches of the coil.

4. In an apparatus for operating on an armature coil with end portions and longitudinal stretches, a frame provided with a longitudinal guide bar, carriages splined on the guide bar and provided with means for adjusting their resistance to sliding movement, means for engaging with the end portions of an armature coil carried by the said carriages, and front and rear arms pivoted to the frame and provided with means for engaging with the longitudinal stretches of the coil.

5. In an apparatus for operating on an armature coil with end portions and longitudinal stretches, a frame provided with slideable supports for engaging with the end portions of an armature coil, front and rear arms pivoted to the said frame and movable crosswise of the coil, front and rear bars extending between the said arms, and means for engaging with the longitudinal stretches of the coil carried by the said bars.

6. In an apparatus for operating on an armature coil with end portions and longitudinal stretches, a frame provided with slideable supports for engaging with the end portions of an armature coil, front and rear arms pivoted to the said frame and movable crosswise of the coil, front and rear bars extending between the said arms, and means for engaging with the longitudinal stretches of the coil adjustable longitudinally on the said bars.

7. In an apparatus for operating on an armature coil with end portions and longitudinal stretches, a frame provided with slideable supports for engaging with the end portions of an armature coil, front and rear arms pivoted to the said frame and movable crosswise of the coil, front and rear bars extending between the said arms, and movable clamping devices carried by the said bars and adapted to engage with the longitudinal stretches of the coil.

8. In an apparatus for operating on an armature coil with end portions and longitudinal stretches, a frame provided with slideable supports for engaging with the end portions of an armature coil, front and rear arms pivoted to the frame and movable crosswise of the coil, sleeves adjustable longitudinally on the said arms, front and rear bars arranged parallel to each other and secured to the sleeves of the arms to which they pertain, and means for engaging with the longitudinal stretches of the coil carried by the said bars.

9. In an apparatus for operating on an armature coil with end portions and longitudinal stretches, a frame provided with slideable supports for engaging with the end portions of an armature coil, front and rear

arms pivoted to the said frame and movable crosswise of the coil, and adjustable stops for the arms carried by the frame, said arms being provided with means for engaging 5 with the longitudinal stretches of the coil.

10. In an apparatus for operating on an armature coil with end portions and longitudinal stretches, a frame provided with uprights and a bar secured between the up- 10 rights, means for engaging with the end por-

tions of an armature coil carried by the said bar, pins projecting inwardly from the uprights under the said bar, and front and rear arms pivoted on the said pins and movable crosswise of the said bar and provided with means for engaging with the longitudinal stretches of the coil. 15

In testimony whereof I have affixed my signature.

JESSE F. COMSTOCK.
